UNITED STATES PATENT OFFICE.

WILLIAM W. SLOCUM, JR., OF REED CITY, MICHIGAN.

LOCOMOTIVE ASH-PAN.

SPECIFICATION forming part of Letters Patent No. 320,183, dated June 16, 1885.

Application filed March 21, 1885. (No model.)

To all whom it may concern:

Be it known that I, WILLIAM W. SLOCUM, Jr., of Reed City, county of Osceola, Michigan, have invented a new and Improved Locomotive Ash-Pan, of which the following is a full, clear, and exact description.

The object of my invention is to provide a new and improved ash-pan for locomotives which can be dumped at the will of the fireman.

The invention consists in the arrangement and combination of parts and details, as will be fully set forth and described hereinafter.

Reference is to be had to the accompanying drawings, forming part of this specification, in which similar letters of reference indicate corresponding parts in all the figures.

Figure 1 is a longitudinal sectional elevation of my improved locomotive ash-pan on the line xx , Fig. 2, the pan being closed. Fig. 2 is a cross-sectional elevation of the same on the line yy , Fig. 1. Fig. 3 is a longitudinal sectional elevation of part of the same, the pan being open. Fig. 4 is a longitudinal sectional elevation of part of a modification, the pan being open; and Fig. 5 is a side view of the locomotive-boiler, showing the ash-pan and damper attachment.

The bottom of the ash-pan A is formed of a series of transverse slats, B, provided with end pivots, C, which are passed to apertures in bars D, secured on the inner surfaces of the sides of the pan at the bottom edges. The edges of the slats B are provided with rabbets E for receiving the upper edges of the adjacent slats when the bottom of the pan is closed. The said rabbets are formed by half-beads F, formed on the under sides of the slats at the bottom edges, and projecting beyond the said bottom edges, and, if desired, half-beads G may be formed on the under sides of the slats near the upper edges. From the upper surface of each

slat B a lug, I, projects, the upper ends of the said lugs being pivoted in a bar, H, having a U-shaped cross-section and extending over the 45 slats. If desired, two lugs I may be formed on each slat, and then the lugs are pivoted to two bars. The bars H or the two bars are connected with a rod, J, which extends to the cab, and is used for swinging the slats up or 50 down. The rod J is passed through one end of the ash-pan. In case the ash-pan is of sufficient height to swing the slats B upward, the pivots C are arranged at the bottom edges of the slats, as shown in Figs. 1, 2, and 3; but 55 when the ash-pan has not sufficient height to swing the entire slats upward the pivots are arranged short distances from the bottom edges, parts of the slats swinging up and parts swinging down. In the front of the ash-pan 60 an upwardly-projecting part, M, is formed, which is provided in its top with a damper-valve, N, and at its bottom with a valve-gate, O, which can be opened to clean the ash-pan. When the valve N is raised, the air strikes the 65 front of the fire-box P, passes down through the compartment M into the ash-pan, and up through the grate, whereby the air is heated before it passes through the coals, which is a great advantage. It also excludes snow, &c., 70 in bad weather.

Having thus described my invention, I claim as new and desire to secure by Letters Patent—

The combination, with an ash-pan, of a compartment, M, formed on the front end of the 75 same and in front of the front part of the fire-box, and of the damper-valve N in the top of the compartment M, substantially as herein shown and described.

WILLIAM W. SLOCUM, JR.
